UNITED STATES PATENT OFFICE.

BERNIS M. SHIPLEY, OF DAYTON, OHIO, ASSIGNOR TO THE NATIONAL CASH REGISTER COMPANY, OF DAYTON, OHIO, A CORPORATION OF MARYLAND.

CASH REGISTER.

Application filed April 22, 1926. Serial No. 103,818.

This invention relates to cash registers, and more particularly to those of the type shown in the patent, to F. L. Fuller, No. 1,242,170, issued October 9, 1917, and the 5 co-pending application of B. M. Shipley, Serial No. 686,564, filed January 16, 1924.

The principal object of this invention is to enforce the positioning of an adding and subtracting totalizer with the adding wheels 10 thereof in operative position, after an operation in which a negative balance was printed, in which operation the totalizer was moved to a position wherein the subtracting wheels were in operative position.

With these and incidental objects in view, the invention consists of certain novel features of construction and combinations of parts, the essential elements of which are set forth in appended claims, and a preferred 20 form of embodiment of which is hereinafter described with reference to the drawings, which accompany and form part of this specification.

Of said drawings:

25 Figure 1 is a vertical sectional view taken through the machine just to the right of one of the banks of amount keys.

Figure 2 is a view in detail side elevation of the motor bar and a portion of the release 30 mechanism.

Figure 3 is a view in detail side elevation of a portion of the release mechanism.

Figure 4 is a vertical sectional view through the machine taken just to the right 35 of the balance bank of keys.

Figure 5 is a view in rear elevation of the upper totalizer line, which carries the adding and subtracting totalizer, together with the mechanism for shifting this line laterally.

40 Figure 6 is a detail view in side elevation of the total lever plate and some of the mechanism which co-operates therewith.

Figure 7 is a detail side view of the total 45 lever locking mechanism in the position which is occupied on a normal adding operation.

Figure 8 is a detail side view of the mechanism shown in Figure 7 with the parts in their locking positions.

50 Figure 9 is a fragmentary view showing the total lever and locks therefor.

General description.

The machine to which the present embodi-

ment of the invention is shown applied, is 55 provided with an adding and subtracting totalizer, which is very similar in construction and operation to that shown in the Fuller patent and the Shipley application above referred to. Any desired amount may either 60 be added to or subtracted from this totalizer by means of a single set of actuators. When addition is being accomplished, the adding wheels are in co-operative relation with the actuators, and when a subtraction is to be 65 made, the totalizer is shifted laterally so that the subtracting wheels thereof are in cooperative relation with said actuators. Should a greater amount be subtracted from the totalizer than is standing thereon, a 70 negative balance on the subtracting wheels results. It is possible, if desired, to print this negative balance and reset the subtracting wheels to zero. It is evident that should this operation take place the adding wheels 75 will all stand at 9, when the subtracting wheels stand at zero, and with the machine in this condition, if an amount is added on the next operation the result will, of course, be incorrect. Means is therefore provided 80 by this invention to lock the total lever in the position in which it was placed to take the negative balance and prevent its return to a normal adding position, until the machine has been given a single blank operation. The object of this blank operation is to move the totalizer to the adding position 85 and to reset the adding wheels to zero, thereby printing the 9's. The totalizer is now in condition to receive entries. The means for accomplishing this result will now be described.

Keyboard.

The machine to which the invention is applied is provided with a plurality of banks 95 of amount keys 30 (Fig. 1), slidably mounted in a key frame 31, supported by two rods 32, mounted in the side frames 33 of the machine. These amount keys 30 are normally held in their outer undepressed positions by means of springs (not shown). When a key 30 is depressed, it is latched in its depressed position by the engagement of a shoulder projecting therefrom, with a stud carried by a movable detent bar 34, such as is well known in all machines of this type.

Appropriate to each bank of amount keys 105 is a zero stop pawl 35, which is fast on a

short shaft 36, supported by the key frame 31. When any key in its appropriate bank is depressed, the zero stop pawl 35 therefore is rocked counter-clockwise to its ineffective position through the agency of a hooked link 37, which pivotally supports the lower end of the detent bar 34, and which cooperates with a pin 38 projecting from the side of an arm fixed to said shaft 36.

- 10 In addition to the amount keys, there are usually three banks of transaction keys. In this application only one of these banks is shown (Fig. 4), as the other banks of transaction keys have nothing whatever to do with the invention herein. This bank of keys is identical with the bank of keys shown in Fig. 13 of the above-mentioned Shipley application. The bank of keys shown in Fig. 4 will be known herein as the balance bank.
- 15 It is provided with five keys. The two lowermost keys 39 are subtracting keys and the three upper keys 40 are adding keys. All of these keys are mounted in a manner similar to the amount keys, in a key frame 31, supported by the rods 32. This bank is also provided with a zero stop pawl 35, identical with that previously described.

The keys 39 and 40, when depressed, are latched in their depressed positions by means 30 of hooks 41, projecting from a detent pivotally supported detent bar 42, and cooperating with pins 43 on the keys. Suitable means are provided for releasing the keys at the end of each operation.

35 Release mechanism.

In all machines of this type there is a release shaft which in this case is a shaft 50 (Figs. 2, 3 and 4). This shaft is adapted to be rocked in a clockwise direction by means 40 of a powerful spring, which is not shown in this application, as this spring with its cooperating mechanism is very well known in machines of this type. In the normal position of the parts, the release shaft 50 is prevented from being rocked under the influence of the above mentioned spring by the engagement of a half-round stud 51 (Fig. 3), carried by an arm 52, fast to the shaft 50, with 50 an arresting arm 53 loose on a shaft 55. So long as the arresting arm 53 remains in alignment with the flat face of the half-round stud 51, the shaft 50 cannot be rocked clockwise by the spring above mentioned, to release the machine.

When the proper keys in the keyboard have been depressed, the machine is adapted to be released by a motor bar 56 (Fig. 2), the shank of which has a bifurcated end 57, 60 adapted to embrace a pair of studs 58, carried by a plate 59, which in turn is slidably mounted on a pair of studs 60 and 61, supported by the machine side frame. The plate 59 also carries a pin 62 projecting through 65 the right hand side frame of the machine

(not shown in this figure), which pin cooperates with the bifurcated end of one arm of a lever 63, pivoted on a stud 64 on the inside of the righthand side frame. At its opposite end, the lever 63 carries a pin 65, which projects through the bifurcated end of an arm 66, loose on the shaft 55, also supported by the machine side frame. The arm 66 is made integral with a hook member 68 by means of a yoke 69. Depression of the motor bar 56 rocks, the hook member 68 clockwise about the shaft 55, as shown in Fig. 2.

The hook 68 takes over a pin 70 carried by an arm 71 to rock the arm 71 clockwise upon the clockwise movement of said hook member. Integral with the arm 71 is a bifurcated arm 72 connected thereto by a yoke 73. The bifurcated portion of the arm 72 embraces a pin 74 carried by the arresting arm 53 which normally obstructs the movement of the stud 51, and thereby prevents the release of the machine. Therefore, when the arm 71, yoke 73 and arm 72 rocks clockwise, it can be seen from Figs. 2 and 3 that the arresting arm 53 rocks counter-clockwise about the shaft 55 to free the stud 51 arm 52 and release shaft 50. As soon as this arresting arm is raised out of the path of the stud 51, the arm 52 and shaft 50, are rocked clockwise under the influence of the before-mentioned spring (not shown) to permit operation of the cash register. The stud 51 is then positioned between the arresting arm 53, and a locking arm 54, loose on the shaft 55, and connected to the arresting arm 53 by means of a spring 75. The locking arm 54 prevents release of the machine until after the motor bar is permitted to return to its outermost position, after the operation of the machine has been completed, in the well known manner, and is fully disclosed in the Fuller Patent, No. 1,242,170, above referred to.

110 Differential mechanism.

The differential mechanism of the machine is employed to differentially operate the different totalizers and to select them for operation, and also to set type carriers in the printing mechanism as controlled by the banks of keys. The amount differential mechanism will be described first.

115 Amount differential unit.

There is one complete differential unit for each amount bank 30, but as they are all identical in construction and operation only one will be described.

To drive the differential mechanism of the machine, a drive shaft 80 (Fig. 1) is provided with a plurality of pairs of cams 81 and 82, each pair cooperating with rollers 83, carried by a Y-shaped lever 84. Each of these levers 84 is pivoted on a corresponding sub-

frame 85. Loosely mounted on a hollow stud 86 carried by the sub-frame 85 is a differentially movable member 87, carrying racks 88 and transfer arms 89 for totalizer pinions 90. The lever 84 at its upper end is connected by a link 91 to a driving segment 92 loose on the stud 86. The driving segment 92 is connected to the differentially movable member 87 by a latch 93, which is supported by a link 94 and a lever 95, pivoted on a radial extension of the corresponding differentially movable member 87. A spring 96 holds the rear end of the latch 93 in engagement with a shoulder on the driving segment 92. When the segment is driven by its cams 81 and 82 the differentially movable member 87 first turns clockwise with its latch to a point where the forwardly extending arm of the lever 95 contacts the inner end of the corresponding depressed amount key 30. Such contact results in disengagement of the latch 93 from the driving segment 92 and engagement of the forward end of the latch with the particular one of a series of notches 97 formed on the inner edge of a locking bar 98 supported by the differential-supporting sub-frame 85, which notch is opposite the latch when it is disengaged from its driving segment 92. Upon return movement of the driving segment to normal position, a pin 99 mounted on the differentially movable member 87 is engaged by the inside of the driving segment 92, and said member is thereby returned to its normal position. If a key 30 is not depressed in an amount bank, the zero stop pawl 35 therefor, operates the latch 93 and arrests the differentially movable member 87 in its "zero" position. However, when a key is depressed, the zero stop pawl 35 is moved out of its operative position, as above described.

The differential mechanism appropriate to the balance bank is shown in Fig. 4. It is very similar to that for the amount banks, except for the fact that instead of the differential member 87 which carries the racks 88 and transfer arms 89, there is substituted a differentially movable member 110. This member is loosely mounted on a stud 86. The mechanism for driving the differentially movable arm or member 110 is identical with that shown for the amount bank and consists of the cams 81 and 82 fast on the drive shaft 80, which serve to rock the Y-shaped member 84, connected by the link 91 to the driving segment 92. The segment 92 is connected to the differentially movable member 110 by a latch 93, similar to the one previously described.

Totalizer line.

As in most machines of this type, this machine is provided with three totalizer lines 111 (Fig. 1). The two lower lines carry the regular adding elements which are well known in these machines and which it is not thought necessary to describe herein. The upper to-

talizer line carries the adding and subtracting totalizer which is constructed in the same manner as that shown in the patent and application above mentioned.

As can be seen from Figs. 1 and 5, there are two totalizer wheels in the adding and subtracting totalizer appropriate to each denomination in the machine. These wheels comprise an adding wheel 112 and a subtracting wheel 113. Fast to the adjacent sides of each pair of wheels are bevel gears 114 and meshing with these bevel gears are two bevel pinions 115 carried by a short shaft 116 supported by the totalizer supporting rod 120. It is apparent that this construction causes the totalizer wheels 112 to turn in a direction opposite to that in which the totalizer wheels 113 turn.

Totalizer shifting mechanism.

As it is the upper totalizer line which carries the adding and subtracting totalizer with which the present invention is chiefly concerned, the description of the mechanism for shifting this totalizer line laterally will be given herein. The totalizer elements 112 and 113 are journaled on the rod 120 which is supported at its ends in arms 121 and 122 (Fig. 5) slidably mounted on a shaft 123 carried by the machine side frames, as shown in the patent and application referred to. The arm 121 has a projecting socket 124 in which is fastened a rod 125 carrying a roller 126. This roller projects into a cam groove 127 formed in a cam 128 loosely mounted on a stud 129 projecting from the adjacent side frame 33. This cam is rotated to different extents under control of the balance bank of keys, and it can be seen from Fig. 5 that during the movement of this cam, the roller 126, rod 125 and arm 121, which supports one end of the rod 120, and the adding and subtracting totalizer, is shifted from a position in which the subtracting pinions 113 of the totalizer are in cooperative relation with the actuators 83, to a position in which the adding pinions 112 are in such cooperative relation or vice versa.

The means for moving the cam 128 differentially will now be described. Integral with this cam is an arm 130 to which is pivoted the lower end of a link 131 which at its upper end is fast on an arm 132 secured to one end of a shaft 133 (Figs. 5 and 4) supported by the side frames 33 of the machine. This train of mechanism is shown in elevation in Fig. 16 of the above-mentioned Fuller Patent, No. 1,242,170. Fast on the other end of the shaft 133 is a segment 134 to which is fastened the upper end of a link 135, (see also Fig. 4) such as is well known in a machine of this class. At its lower end the link 135 is pivoted to an arm 136 loosely mounted on a rod 137 also supported by the machine side frames 33. About midway of the link 135 is a roller 138 embraced by the bifurcated portion 139 of a

beam 140, which at its opposite end is pivoted to the differentially movable member 110 for the balance bank (Fig. 4).

It is apparent that when the differentially movable member 110 is differentially adjusted under the control of the keys 39 or 40 in the balance bank, the left hand end of the beam 140 will be also differentially adjusted therewith. During the operation of the machine, a roller 141 carried by the Y-shaped member 84 comes into contact with the bottom edge of the beam 140 to shift the righthand end of this beam to a position corresponding with the position in which the differentially movable member was arrested, and through the roller 138, moving the link 135 differentially. This differential movement of the link 135 adjusts the segment 134, shaft 133, arm 132, (Fig. 5), link 131, arm 130 and cam 128 in accordance with the position in which the latch 93 of the balance bank was disengaged from its driving segment 92 and through the cam, adjusts the adding and subtracting totalizer to either its adding or subtracting position.

The elements 133, 132, 131 and 128 of this application correspond to the elements 349, 348, 347 and 344, shown in Fig. 16, of the Fuller patent above referred to. The cam race 127, Fig. 5, is formed with two relatively-offset straight portions and a connecting camming portion. The roller 126 is illustrated herein in the particular straight portion of the cam race which holds the subtraction wheels 113 in alignment with the actuators 88. When the cam is differentially positioned under control of any one of the keys 39, the cam 127 maintains the subtracting totalizer elements 113 in alignment with the actuators 88. Any one of the keys 40 differentially controls the cam 128 to cause the camming portion of the cam race 127 to shift the subtracting totalizer elements 113 out of alignment with the actuators 88 and the adding elements 112 into alignment therewith. There are two keys 39 and three keys 40 shown in the present application. These keys are illustrative only, as any number of adding or any number of subtracting keys can be used, and the shape of the cam race 127 formed accordingly. The number of keys selected, in illustrating the invention herein, is the same as in the above-mentioned co-pending Shipley application, Serial No. 636,564, and reference may be had thereto for a typical system of control for the adding and subtracting totalizers. By referring to Fig. 57 of the co-pending application, it will be seen that the keys corresponding to the keys 39 of the present application are designated "Credit balance" and "Debit correction" keys; and the keys 40 are designated "Credit correction", "Forward balance", and "Closing balance" keys. Hence the operator when he lists

a "Credit balance" or a "Debit correction" item presses the appropriate key 39, either of which selects the subtraction side of the totalizer. And when the operator comes to a "Credit correction" item, a "Forward balance" or a "Closing balance", he presses the appropriate key 40 any of which selects the adding side of the totalizer. Obviously but two keys 39, 40 could be used, but it assists the operator to provide a series of keys bearing the various indicia appropriate to the amounts to be listed, thereby relieving him of the necessity of remembering that he must depress a "Subtract" key, for instance, when listing a "Credit balance".

It can be seen that should the latch 93 of the balance bank be disengaged from its driving segment 92 in either the "zero", "1" or "2" positions, the cam 128 is not moved sufficiently to shift the adding and subtracting totalizer from the position shown in Fig. 5 so that when the latch 93 is disengaged in any of these positions, the totalizer remains in its subtracting position. If, however, the latch is disengaged in the fifth, seventh, eighth or ninth positions of the balance bank, the cam 128 shifts the adding and subtracting totalizer laterally to bring the adding wheels 112 into cooperative relation with the actuators 85. The axial shifting movement of the totalizer takes place during the period that the differentially movable member 110 passes from the "2" to the "5" position or vice versa.

Totalizer engaging mechanism.

Means is, of course, provided for engaging the totalizers on the three totalizer lines with the actuators after the lines have been adjusted to select the desired totalizer for operation. However, as the engaging mechanism has nothing whatever to do with the present invention, it is neither shown nor described in this application. Reference can be made to the above mentioned patent and application if any description of the engaging mechanism is desired.

Total printing operation.

In order to take a total from any of the totalizers in the present machine, mechanism is provided which changes the time of engagement of the selected totalizer with the actuators, so that it is moved into engagement with the actuators at the beginning of an operation. The totalizer wheels are then turned backwards as the actuators are operated, until they reach their zero positions, when the latches 93 are automatically disengaged from the respective driving segments 92 in a manner which is well known in the art and which will not be described herein. After the totalizer wheels are returned to zero they are disengaged from the actuators thereby leaving them in the zero position. If a sub-total is to be taken this disengagement

ment does not take place until the actuators are returned to zero thereby restoring to the totalizer wheels the amount taken therefrom, as is well known in machines of this type. 5 This turn-to-zero movement applies to the adding and subtracting totalizer wheels 112, 113, as well as to the ordinary adding totalizers 90, and either the adding wheels 112 of this totalizer or the subtracting wheels 113 thereof may be positioned to cooperate with the actuators 87.88 to be set to zero. Of course, usually, the adding wheels are the ones selected, as in most cases, the balance on the adding and subtracting totalizer is a positive one. There are instances, however, where the balance on this totalizer is a negative one, such a condition being produced by the subtraction of a greater amount from a lesser. When this occurs, and it is desired 20 to print a total of the amount on the negative wheels 113, these wheels are positioned to cooperate with the actuators 87.88 and the operation is carried out as usual. It is apparent that when the negative wheels of the adding and subtracting totalizer are set to "zero," the positive wheels 112 thereof are turned to "nine," as the settings on the two groups of wheels are always complementary to each other. If, after such an operation has taken 25 place, the machine is operated to add an amount on the adding side of the totalizer, it is evident that a wrong result would be had, and therefore, mechanism is provided to prevent the adjustment of the machine to an adding condition until the adding side of the adding and subtracting totalizer has been in turn reset to zero. This mechanism will now be described.

Total lever.

40 As in all machines of this type, the present machine is provided with a total lever 150 (Fig. 6) which is integral with a total lever plate 151 pivotally mounted on a stud 152 projecting from the right hand side frame 33. The function of the total lever is to control the machine during total printing operations. The total lever selects the totalizer line which is to be rocked into engagement with the actuators, through the provision of three positions of adjustment thereof. The first position of adjustment below the adding position is the position in which the upper or adding and subtracting totalizer 45 line is selected for operation, and it is this position, therefore, with which the present application deals.

50 The movement of the total lever plate 151 accomplishes various functions before the operation of the machine begins. One of these functions is to lock out the amount keys 30, and set up a condition to rock out all of the zero stop pawls 35, as it is not desired that these pawls should be effective on the second 55 cycle of the total printing operation. The

mechanism whereby this is accomplished will now be described. Cut in the total lever plate 151 (Figs. 6, 7 and 8) is a slot 153, with which a roller 154 carried by one arm of a multiple armed lever 155 cooperates. Lever 155 is pivoted on a stud 156 and also loosely mounted on this stud is a link 157 connected to the lever 155 by a slot and pin connection for limited relative movement. It is evident that when the total lever 151 is moved out of its normal adding position in which it is shown in Fig. 6, in either direction, the lever 155 is rocked counter-clockwise. This movement is communicated to the link 157 through a spring 158 to rock the link also in a counter-clockwise direction. The spring 158 is interposed between one arm of the lever 155 and the link 157, its ends being supported on opposed extensions projecting from the arm of the lever and from the link, respectively, the spring tending to hold the lever and link separated as far as the pin and slot connection permits. The link 157 has a cam slot 159 formed therein, with which a roller 160, carried by an arm 161 fast on a shaft 162 cooperates. A counter-clockwise movement of the link 157 rocks the arm 161 and shaft 162 in a clockwise direction. Shaft 162 extends across the entire machine and a portion of the shaft in front of the banks of amount keys 30 (Fig. 1) carries a plurality of arms 163, which in turn, carry a bail 164. Bail 164 normally lies out of the paths of the hooked links 37, and just above a plurality of fingers 165 which are fast on the short shafts 36 which support the zero stop pawls 35 for the various amount banks. It is evident that when the shaft 162 is rocked clockwise by the manual adjustment of the total lever 150 in counter-clockwise direction, the bail 164 shifts into the paths of the hooked links 37 to prevent operation thereof, and of the detent bars 34, and thus prevent depression of the amount keys 30.

55 Also the manual adjustment of the shaft 162 by the total lever 150 and total plate 151, causes the shaft 162 to set mechanism (not herein shown, but disclosed in the patent and in the application before referred to) which last-named mechanism is driven by the machine as it completes its first cycle in total taking operations, to rock the shaft 162 farther in clockwise direction and thereby rock the bail 164 in the same direction to contact with all of the fingers 165 and rock the fingers, the shafts 36 and the zero stop pawls 35, counter-clockwise to their ineffective positions, just prior to the second cycle of a total printing operation.

60 The mechanism appropriate to the first transaction bank or balance bank (Fig. 4) is slightly different. The shaft 162 carries an arm 166 in line with this bank of keys which normally lies just above the pin 167 carried by a short arm 168 fast on the shaft 36 for this bank. The clockwise movement of the shaft 162 by the manual operation of the total lever 163

150 rocks the arm 166 against the pin 167 and, through the arm 168, rocks the shaft 36 and the zero stop pawl for the first transaction banks to its ineffective position.

5 *Total lever locking mechanism.*

Fig. 7 shows the mechanism of the present invention in the position which it occupies when the total lever is in its normal adding position. When the total lever 150 is moved to the first position below its adding position to select the adding and subtracting totalizer for operation, by mechanism shown in the patent and application referred to, the parts 10 assume the positions shown in Fig. 8. The mechanism for locking the total lever 150 in the first position below its adding position, when a total has been printed from the negative side of the adding and subtracting 15 totalizer includes a locking lever 175 pivoted on a member 176 mounted on the rod 137 and supported by another rod 177. This locking lever 175 normally tends to rock in a counter-clockwise direction under the 20 influence of a spring 178 which is stretched between a pin on the lever and a pin on a projecting arm 179 of the member 176. The upper arm of the locking lever 175 has a shoulder 180 cut therein to cooperate 25 with the pin 154 carried by an arm of the multiple-armed lever 155 above mentioned. The lower arm of the locking lever 175 carries a roller 181 to cooperate with the periphery of a disc 182 loose on the rod 137, but pinned to the differentially adjustable arm 136 previously mentioned. This disc is recessed, as at 183, with which recess the roller 181 is adapted to cooperate. The 30 recess is preferably made long enough to correspond to the first and second key positions, that is, to the positions to which the differential mechanism is adjusted when either of the two subtraction keys 39 is depressed and the machine operated.

35 When the total lever 150 is in the adding position, as seen in Figures 6 and 7, the spring 178 holds the upper arm of the locking lever 175 against roller 154 mounted in the lever 155 with the shoulder 180 ineffective.

40 Normally, the recess 183 of the disk 182 lies opposite the roller or stud 181 on the lower arm of the spring-drawn locking lever 175, and depression of either of the subtraction keys 39 followed by an operation of the 45 machine will cause the differential mechanism to adjust the disk 182 in clockwise direction, but as stated the length of the recess 183 is such that it will still lie opposite the projection 181 on the lower arm of locking lever 175. It is only when some one of the adding keys 40 is depressed and the machine operated, that the disk 182 will be differentially 50 adjusted to position an unmutilated part of the periphery of the disk 182 opposite the projection 181 on the locking lever 175.

In this latter event, the disk will retain the locking lever 175 ineffective, in totaling operations when the total plate 151 is rocked.

It is apparent that when the lever 155 is rocked counter clockwise by the walls of the slot 153 in the total lever plate 151, when the total lever is operated, the locking lever 175 is rocked counter-clockwise to the position shown in Fig. 8, if the recess 183 of disc 182 is in position to receive the roller 181. When 70 the disk permits the latch 175 to rock to the position shown in Fig. 8 the shouldered upper end 180 of the locking lever 175 snaps beneath the roller 154 on lever 155, and so long as the parts remain in this position, the lever 155 and the total lever plate 151 cannot be returned to their normal adding positions. The control of the locking device is, therefore, found in the disc 182. This disc is adjusted differentially in accordance with the adjustment of the differentially movable member 110 for the balance bank, as shown in Fig. 4. In Figs. 4 and 7, the disc is shown in its zero position. In this position it is evident that the locking lever 175 cannot be effective. If, however, the total lever 150 is moved to its first position below its adding position, and one of the keys 39, in the first or second positions in the balance bank is depressed, the latch 93 for the balance bank will be disengaged from its driving segment 92 in either the first or second position, and therefore, the disc 182 will be so positioned that the recess 183 thereof lies beneath the roller 181 on the locking lever 175. This lever is, therefore, free to move to its locking position under the influence of the spring 178. With the total lever moved to its first position below adding and one of the keys 39 depressed, the subtracting side of the adding and subtracting counter will be selected for operation, and therefore, the negative balance thereon will be printed. It is evident that after such an operation has taken place it is impossible to move the total lever 150 to its normal adding position until the locking lever 175 has been disabled.

The manner in which the total lever can be freed so that adding operations of the machine can be resumed will now be described. This is accomplished by depressing the motor bar 56 and giving the machine a single blank operation of two cycles while the total lever remains in its adjusted position.

The locking lever 175, when effective, lies in the path of the roller 154 on lever 155, which roller also traverses the cam slot 153 in the total plate 151.

Normally the roller 154 lies at the apex 125 of the node in the cam slot, but when the total plate 151 is adjusted, it shifts the node away from the roller 154 and rocks the lever 155 carrying the roller 154.

And with the disk 182 positioned so that 130

the roller 181 on locking lever 175 drops into the recess 183 in the disk, the locking lever 175 will snap behind the roller 154 on the lever 155 to hold it in its rocked position.

5 By locking the lever 155 against rocking to its normal position, the locking lever 175 locks the total plate 151 against restoration.

The total plate 151, when adjusted to any position other than its adding position, operates through the linkage heretofore set forth, to locate the bail 164 (Fig. 1) so that it will disable the zero stop pawls 35, at the end of the first cycle of the totaling operation, and of course, if the total plate 151 is locked 15 against restoration to its adding position, the bail 164 is held in its adjusted position ready to disable the zero pawls 35 at each complete totaling operation of the machine. On the first cycle of a total taking operation, the 20 zero stop pawl 35 for the balance bank will be in its ineffective position, as the total lever 150 is out of its adding position, and therefore, the differentially movable member 110 is not arrested at the "zero" position 25 but continues to turn clockwise. As there are no keys depressed in the transaction bank, (Fig. 4) a special mechanism is provided which disengages the latch 93 of this bank in the "3" position, which position corresponds 30 to the lowermost key 40, to select the adding side of the adding and subtracting totalizer for operation. This occurs during the first cycle of a total taking operation.

During the first cycle of such operation 35 also, the zero stop pawls 35 for the amount banks arrest the denominational actuators 88 in their zero positions, but on the second cycle of the total taking operation, the totalizer selected during the first cycle is shifted into engagement with the actuators, after 40 which the actuators advance, and because of the displacement of the zero stop pawls 35 by the bail 164, the actuators 88 continue to advance under control of the selected totalizer, 45 until arrested by the long teeth of the totalizer wheels in the usual manner, fully disclosed in the Fuller patent heretofore mentioned. Hence the operation of the actuators 88 returns the adding wheels 112 to 50 "zero." The automatic latch disengaging mechanism includes an elbow lever 190 (Fig. 4) loosely mounted on the stud 86 for the balance bank. One arm of the elbow lever 190 has a slot 191 cut therein, through which 55 projects a pin 192 carried by the forwardly extending arm of the bell crank lever 95 which supports the latch 93 for this bank. The upper end 193 of the elbow lever 190 is adapted to cooperate under certain conditions with a pin 194 carried by an arm 195 loose on a cross rod 196. The pin 194 is normally held out of the path of the end 193 of the lever 190, by a triangular abutment 197, which is riveted to the side of the total 60 lever plate 151. The arm 195 normally tends

to rock in a counter-clockwise direction due to a spring 198 stretched between a pin on the arm 195 and any suitable part of the mechanism. It can be seen that whenever the total lever 150 is moved either up or down out of its normal adding position, the abutment 197 is removed from beneath the pin 194 and the spring 198 will then rock the arm 195 counter-clockwise until the pin 194 rests against the differential supporting 70 frame 85 for the balance bank. When the arm 195 is in this position and the machine is operated, the differentially movable member 110 will move clockwise until the end 193 of elbow lever 190 strikes the pin 194 to 80 arrest the differential member 110. The bell crank lever 95 is then rocked counter-clockwise, due to its slot and pin connection with the elbow lever 190, and the latch 93 is disengaged from the shoulder of the driving 85 segment 92.

The automatic disengagement of the latch 93 of the balance bank in the fifth position as just above described causes the adding side of the adding and subtracting totalizer to be 90 moved to operative position and rotates the disk 182 to shift the lever 175 out of contact with the stud 154. The actuators 88 after the engagement of the adding wheels 112 therewith, reversely rotates the adding wheels 95 from their "9" positions (in which they were left when the negative total was taken from the subtracting wheels 113) and resets the adding wheels to "zero".

The controlling disk 182 also displaces the 100 locking lever 175 to release the total key lever 150, which may then be restored manually or otherwise to its "adding" position, whereupon the machine is cleared and in readiness for a new series of operations.

When the total lever 150 is shifted to the first upper, or "Read" position, and the machine is operated with a key 39 depressed, the negative total is printed, but the amount is again added on the totalizer, in a manner well known in the art. During this operation, the disk 182 is positioned in the same manner as during reset operations, and the locking lever 175 holds the total lever 150 against restoration to its adding position in exactly the same 110 manner as during "Reset" operations. Before the total lever 150 can be returned from the first "Read" position to its adding position, it is necessary to make a blank operation, just as during "Reset" operations, by 115 depressing the motor bar, but no control key. During this operation, the amount on the positive side of the totalizer is printed, but the totalizer is not reset to zero. This blank operation after a "Read" operation performs 120 no particular function, other than to unlock the total lever, but it is a necessary incident to the construction disclosed herein.

As shown in Fig. 9, two removable key locks 125 are provided, the upper lock preventing 130

movement of the total lever 150 into any of the "Read" positions, and the lower lock preventing movement into any of the "Reset" positions, except that corresponding to the 5 balance bank. These locks are under control of the proprietor or other authorized person, and the operator can move the total lever, only into the "adding" and the "balance reset" positions. Those locks in combination 10 with the total lever locking mechanism shown in Figs. 6, 7 and 8, constitute means compelling the clearing of the adding wheels after a negative total has been printed.

15 *Operation.*

A brief description of the operation of the machine will now be given. The amounts to be added, or subtracted, are set up on the keyboard in the manner set forth in the above- 20 mentioned patent and application. If a total is to be taken from the adding and subtracting totalizer 112.113, the total lever 150 is set to either the first position below "add" position, to condition the machine for a "Reset" operation, or to the first position above the "add" position, to condition the machine for a "Read" operation, and the proper key 39 or 40 is depressed. If a negative total is desired, the proper key 39 is depressed, and 25 the machine is released for operation. During the operation of the machine, the disk 182 is positioned, under control of the key 39 to permit the locking lever 175 to engage the stud 154, and prevent shifting the total lever 30 150 back to the "add" position. At the end of this operation, all the positive totalizer elements 112 are standing at "nine", and before the total lever can be shifted to permit an amount to be added thereon, it is necessary 35 to make a blank operation, during which the positive totalizer wheels 112 are automatically rest to "zero" and the locking lever 175 is shifted out of contact with the stud 154 to permit the total lever to be shifted back 40 to its "add" position.

When the machine is operated, with the total lever in the first upper, or "Read", position and a key 39 is depressed, the total lever is locked at the end of the operation 45 of the machine. However, this locking of the total lever during "Read" operations has no function, but is a condition which is inherent in the present embodiment of the invention. Therefore, it is necessary to make 50 a blank "Read" operation, after reading the negative total, but inasmuch as the positive wheels 112 are not reset to "zero" during "Read" operations, the proper total is still standing on the totalizer after such an operation, and the total lever is released in the 55 same manner as during the blank operation after a "Reset" operation.

While the form of mechanism herein shown and described is admirably adapted to fulfill the objects primarily stated, it is to be 60

understood that it is not intended to confine the invention to the one form or embodiment herein disclosed, for it is susceptible of embodiment in various forms all coming within the scope of the claims which follow. 70

What is claimed is:—

1. In a machine of the class described, the combination of a total lever having an adding position and a plurality of total-taking positions, and automatic means for locking 75 said total lever against a return movement to adding position after a certain total-taking operation.

2. In a machine of the class described, the combination of a total lever having an adding 80 position and a plurality of total-taking positions, an adding and subtracting totalizer under control of said total lever, means for taking a negative total from said totalizer, and automatic means for preventing the return 85 of the total lever to its adding position after such a total has been taken.

3. In a machine of the class described, the combination of a total lever having an adding 90 position and a plurality of total-taking positions, an adding and subtracting totalizer under control of said total lever, said totalizer having a series of adding elements and a series of subtracting elements, means for taking 95 a total from said subtracting elements, and means to enforce the return of the totalizer to a position in which the adding elements will be operated.

4. In a machine of the class described, the combination of a total lever having an adding 100 position and a plurality of total-taking positions, an adding and subtracting totalizer under control of said total lever, said totalizer having a series of adding elements and a series of subtracting elements, means for taking 105 a total from said subtracting elements, and means to enforce the return to zero of the adding elements following the taking of a total from the subtracting elements.

5. In a machine of the class described, the combination of a total lever having an adding 110 position and a total-taking position, a plate integral with said lever having a slot cut therein, a pin projecting through said slot, an arm carrying said pin, and a member adapted 115 to cooperate with said pin to prevent the return of said total lever from total-taking to adding position after certain operations of the machine.

6. In a machine of the class described, the combination with an adding and subtracting totalizer; of a total lever having an adding position and a total-taking position, a plate integral with said lever having a slot cut 120 therein, a pin projecting through said slot, an arm carrying said pin, a locking member adapted to assume a position beneath said pin on certain total-taking operations of the machine in order to prevent the return of the total lever to its adding position, and means 125 130

- to prevent the movement of said locking member on other total taking operations.
7. In a machine of the class described, the combination of a total lever having an adding position and a total-taking position, a plate integral with said lever having a slot cut therein, a pin projecting through said slot, an arm carrying said pin, a locking member adapted to assume a position beneath said pin on certain total-taking operations of the machine in order to prevent the return of the total lever to its adding position, and a disk cooperating with said locking member and adapted to control the position thereof.
- 10 8. In a machine of the class described, the combination of a total lever having an adding position and a total-taking position, a plate integral with said lever having a slot cut therein, a pin projecting through said slot, an arm carrying said pin, a locking member adapted to assume a position beneath said pin on certain total-taking operations of the machine in order to prevent the return of the total lever to its adding position, a disk co-20 operating with said locking member, and differential means for positioning said disk.
9. In a machine of the class described, the combination of a total lever having an adding position and a total-taking position, a plate integral with said lever having a slot cut therein, a pin projecting through said slot, an arm carrying said pin, a locking member adapted to assume a position beneath said pin on certain total-taking operations of the ma-30 chine in order to prevent the return of the total lever to its adding position, a notched disk cooperating with said locking member, differential means for positioning said disk, and a bank of keys for controlling said dif-40 ferential means.
10. In a machine of the class described, the combination of an adding and subtracting totalizer comprising adding and subtracting wheels, means for entering amounts therein, means to clear the subtracting wheels, and means to prevent entry of an amount in the adding wheels during an operation immediately following an operation in which the subtracting wheels are cleared.
- 45 11. In a machine of the class described, the combination of an adding and subtracting totalizer, adding totalizers, means for entering amounts additively and subtractively on the adding and subtracting totalizer, and additively on the adding totalizers, means to take the positive and negative totals on the adding and subtracting totalizer, and totals on the adding totalizer, and means for preventing the entry of items on any totalizer during an operation immediately following a negative total taking operation.
- 50 12. In a machine of the class described, the combination of an adding and subtracting totalizer, differentials for entering amounts additively and subtractively in said totalizer,

means for controlling said differentials and the totalizer to take the negative total on said totalizer, means under control of one of said differentials to prevent an item entering operation immediately following a negative total taking operation, means for releasing the machine for operation, and means positioned under control of said total taking controlling means for controlling said last-named differential to take a positive total upon operation of said releasing means.

70 13. In a machine of the class described, the combination of an adding and subtracting totalizer, means for entering amounts thereon, means for taking positive and negative totals from said totalizer, and means set up during a negative total operation for necessitating a positive total taking and clearing operation prior to a subsequent item entering operation.

80 14. In a machine of the class described, the combination with a plurality of sets of totalizers; actuators therefor; means to select any set of totalizers for operation by their actuators; and a total lever having a normal position and a total taking position; of a locking lever adapted to latch the total lever in one of its adjusted positions; and controlling means set by the totalizer-selecting means to determine the effectiveness of the locking lever.

90 15. In a machine of the class described, the combination with a plurality of sets of totalizers; actuators therefor; means to select any set of totalizers for operation by their actuators; and a total lever having a normal position and a total taking position; of a locking lever adapted to latch the total lever in one of its adjusted positions; controlling means set by the totalizer-selecting means to determine the effectiveness of the locking lever; and automatic totalizer-selecting means to adjust the controlling means upon a blank operation of the machine, to disable the locking lever.

100 16. In a machine of the class described, the combination with a total lever adjustable to a plurality of positions; of a locking member to latch the total lever against restoration when the lever is shifted to a predetermined one of its positions; an adjustable release means for the locking lever; and means to position the release means.

110 17. In a machine of the class described, the combination with a total lever adjustable to a plurality of positions; of a locking member to latch the total lever against restoration when the lever is shifted to a predetermined one of its positions; an adjustable disk to control the effectiveness of the locking lever; and differential means to position the disk.

120 18. In a machine of the class described, the combination with a total lever adjustable to a plurality of positions; of a locking means for the total lever when the latter is shifted

to one of its adjusted positions; a lock controlling means adjustable to a plurality of positions; and manipulative devices to determine the position to which the lock-controlling means shall be adjusted.

19. In a machine of the class described, the combination with an adjustable total lever; of a locking means to lock the lever in one of its positions; adjustable lock control

means to determine the effectiveness of the locking means; manipulative devices to determine the position of the lock control means; and means operable automatically upon a blank operation of the machine to adjust the lock control means to disable the locking means.

In testimony whereof I affix my signature.
BERNIS M. SHIPLEY
